OIL BURNER.

Application filed September 12, 1924. Serial No. 737,292.

This invention relates to oil burners and will be herein disclosed as embodied in a burner of the gravity feed type designed especially for domestic use.

5 It is the chief object of the invention to improve the construction of oil burners of the domestic type with a view to reducing the manufacturing expense, facilitating their installation and the making of repairs and adjustments while in use. The invention also involves features designed to increase the efficiency of burners of this type and to minimize the deposits of carbon or soot.

10 The nature of the invention will be readily understood from the following description when read in connection with the accompanying drawings, and the novel features will be particularly pointed out in the appended claims.

15 20 In the drawings,

Figure 1 is a perspective view, partly broken away, of a burner embodying the present invention;

25 Fig. 2 is a vertical, central, cross-sectional view of the burner shown in Fig. 1;

Figs. 3 and 4 are perspective views of the oil nozzle; and

Fig. 5 is a perspective view of a part attached to the oil nozzle.

30 The construction shown comprises a horizontal burner bowl 2 supported on legs 3. The bowl has a central enlargement 4 projecting from its upper surface, and a vertical hole 6 is drilled through this enlargement and is tapped to receive an oil supply pipe 5. The oil is supplied by a main tank from which the oil flows by gravity to a float valve chamber, and it is conducted from this chamber to the burner by the pipe 5. The 35 main supply tank and the float chamber are not shown since this arrangement is common in gravity feed burners. Preferably the oil level in the float chamber is maintained somewhat higher than the upper surface of the enlargement 4 in the bowl so that oil will flow freely by gravity into the bowl. The enlargement 4 is provided with grooves concentric with the hole 6 in which wicks 7-7 made of asbestos or similar material are located, these wicks forming baffles over which the oil flows initially when the burner is being started.

40 Seated on the enlargement 4 in the bowl

at the upper end of the duct 6 is an oil nozzle 8, best shown in Figs. 2, 3 and 4. This nozzle comprises a metal disk having a central hole 9 therethrough to receive a threaded stem or handle 10, Fig. 2, and the hole 9 is surrounded by a series of vertical holes or perforations 12 through which the oil flows either in liquid or gaseous form, depending upon the conditions in the burner. That is, when the burner is first started the oil will flow through the holes 12 in the form of a liquid, but after the burner has been in 45 operation for a short time the heat will vaporize the oil before it reaches the nozzle 8 so that normally the oil is in the form of a gas or vapor when it flows through the perforations 12. Preferably a washer 14 is located just above the nozzle 8 and is held in place by a nut 15 where it will throttle to some extent the flow of gas through the holes 12, and will direct the gas outwardly 50 across the upper surface of the nozzle 8.

55 In order to facilitate the gradual vaporization of the oil before it is discharged into the bowl, a rod 16, Figs. 2 and 5, is secured to the lower side of the nozzle 8 where it will project down into the oil supply pipe 5 for a substantial distance. This rod is made of copper or some other good conductor of heat, and it may be secured to the nozzle 8 by being threaded on the stem of the handle 10 that projects through the nozzle. We find that the use of this rod produces a steadier, cleaner, and more economical flame than can otherwise be obtained. Apparently this result is due to the fact that the hot rod produces a slower and more even vaporization 60 of the oil, but whatever the reason for the improved action may be, we have definitely determined that it substantially eliminates fluctuations in the flame and produces a cleaner flame.

65 70 When the burner is in operation there is always some tendency for the oil to break down and carbonize, and while we have found that these deposits of carbon are not serious in the burner shown, it is necessary to remove this deposit from the nozzle occasionally. For this purpose we have made the nozzle easily removable, and provided it with ribs 17 and with a fluted tapered extension 18 that projects for a short distance 75 80 into the oil supply duct 6. The nozzle sim-

ply rests on the flat upper surface of the enlargement 4 and may be readily lifted off its seat and removed from the burner. In removing the nozzle it is preferable to take hold of the handle 10 and turn it to rotate the nozzle, thus scraping off any deposits that have collected on the surfaces in contact with the nozzle. The ribs 17 on the lower surface of the nozzle and the fluted or ribbed construction of the extension 18 facilitate this scraping action. Any deposits of scale or carbon on the nozzle may then be easily wiped off and the nozzle replaced. When the nozzle is returned again to its operative position it should be rotated slightly to remove any particles of carbon or other foreign material that may have collected on the nozzle seat and which would prevent it from seating properly. This construction avoids any possibility of the nozzle sticking, while at the same time forming a tight joint between the nozzle and the bowl. The tapered extension 18 also centers the nozzle in the bowl. A burner cap 20 rests on the bowl 2 but is held in spaced relationship thereto by means of three lugs, one of which is shown at 21, these lugs resting on the edge of the bowl and serving, also, to hold the cap centered with reference to the bowl. A central aperture 22 is provided in this cap to receive the air nozzle. This nozzle comprises a lower upright section 23, an intermediate inclined section 24 and an upper horizontal section 25, these sections being secured together by set screws. It also includes an internally tapered nozzle tip 26 which is secured in the lower tubular section 23 by means of three set screws, one of which is shown at 27, so that it can be adjusted vertically toward and from the bowl 2. This adjustment is desirable to control the amount of air which is delivered to the flame with a given draft, it being understood that the air enters through the section 25 and flows downwardly through the nozzle. Usually the intake end 25 of the nozzle is sealed into the furnace door opening. The lower edge of the nozzle section 23 rests on two lugs, one of which is shown at 28, Fig. 2, and the other being diametrically opposite to it, so that the nozzle can be rocked backward and forward in substantially its own plane. This mounting is convenient for the purpose of adjusting the intake end of the nozzle. The nozzle is supported in its adjusted position by two adjusting screws 29-29 supported in arms 30-30 that project upwardly from the cap 20. It will be observed that the nozzle simply rests on the burner cap 20 and that it may be lifted out of the cap whenever desired to inspect or clean the burner.

When the burner is located in a furnace of unusually large diameter, it preferably is equipped with a flame spreader which may be of the form shown in Figs. 1 and 2. This

spreader simply consists of two semi-circular sections 32-32 having end lugs 33 which fit in sockets provided in the burner cap 20, each section also having a lug 34 which rests on the upper surface of the cap at an intermediate point in the length of the section. Flame spreaders of different diameters may be used and since they simply rest on the cap, they may be installed or removed instantly.

75 All the heavy parts of the apparatus, such as the bowl or base 2, cap 20, and flame spreader 32, are preferably made of cast iron. The oil nozzle 8 may either be made of cast iron or of some more highly refractory metal, such as Monel metal.

70 It is a common practice to equip oil burners with an automatic device arranged to be operated by the overflow of oil from the burner to cut off the supply of oil to the 85 burner. In order to permit the use of such a device with this burner, an overflow pipe 35 is connected with the base or bowl 2. In case the flame is blown out, or accidentally extinguished in any other way, oil will flow 90 through this pipe to the desired point of delivery. A common objection to the overflow arrangements heretofore employed for oil burners is that the overflow pipe includes sharp angles which may easily become 95 plugged. We prefer, therefore, to use an overflow pipe through which a flexible cleaner can be run and which leads straight out of the bowl, as shown, so that the cleaner can run completely into the bowl. The bowl 100 is provided with two outlets into either of which an overflow pipe can be connected, the second outlet being shown in Fig. 2 as closed by the plug 36. Sometimes it is much more convenient to run the overflow pipe from 105 the latter outlet due to the design of the furnace in which the burner is installed.

When the burner is in operation oil flows slowly through the pipe 5 to the bowl 2 and becomes vaporized before it is discharged 110 into the bowl. As the oil vapor or gas flows through the nozzle 8, it meets the hot air current flowing downwardly through the air nozzle and the oil unites with the oxygen of the incoming current of air, producing 115 a flame which is directed outward laterally between the cap 20 and the bowl or base 2. The diameter of the fire so produced may be increased very substantially through the use of a flame spreader, such as that shown 120 at 32.

125 It will now be appreciated that this invention provides an oil burning apparatus which may be manufactured very economically, which is convenient to install and adjust, and in which all the parts are readily accessible so that inspection and repairs can be made very readily. The ease with which the carbon can be removed from the oil nozzle and its seat, and the fact that the 130

overflow pipes can be readily kept open, are important factors in keeping the apparatus in efficient working condition.

While we have herein shown and described the best embodiment of our invention which we have so far devised, we do not desire to be limited to the exact details of the construction shown.

Having thus described our invention, 10 what we desire to claim as new is:

1. An oil burning apparatus comprising, in combination, a burner bowl, an oil supply pipe leading upwardly into said bowl, an air nozzle leading downwardly and terminating close to the point at which the oil is discharged into said bowl, and means supporting said nozzle for tipping adjustment relatively to said bowl.
2. An oil burning apparatus comprising, 20 in combination, a burner bowl, an oil supply pipe leading upwardly into said bowl, an air nozzle leading downwardly and terminating close to the point at which the oil is discharged into said bowl, means supporting said nozzle for swinging adjustment backward and forward, and means adjacent to said bowl for supporting said nozzle in its adjusted position.
3. An oil burning apparatus comprising, 30 in combination, a substantially horizontal burner bowl, an oil supply pipe leading upwardly into said bowl, a burner cap supported by said bowl but spaced above it, a flame spreader removably supported on said cap, and an air nozzle extending upwardly from said cap.
4. An oil burning apparatus comprising, 40 in combination, a burner bowl, an oil supply pipe leading upwardly into said bowl, an air nozzle leading downwardly and terminating close to the point at which the oil is discharged into said bowl, an oil nozzle removably seated on said bowl immediately above the delivery end of said pipe, and an extension from said oil nozzle projecting upwardly into said air nozzle.
5. An oil burning apparatus comprising,

in combination, a substantially horizontal burner bowl, an oil supply pipe leading upwardly into said bowl, an oil nozzle seated 50 on said bowl immediately above the discharge end of said oil pipe, said nozzle having carbon scraping members on its lower surface, and means connected with said nozzle whereby it may be rotated to 55 scrape the carbon from the surfaces engaged by the nozzle.

6. An oil burning apparatus comprising, in combination, a bowl adapted to be supported in a substantially horizontal position 60 and having a central enlargement in its upper surface, an oil supply duct leading upwardly through said bowl and through said enlargement, and a disk-like oil nozzle seated on said enlargement, said nozzle having 65 holes therethrough for the passage of oil and being provided with carbon scraping ribs on its lower side.

7. An oil burning apparatus comprising, 70 in combination, a substantially horizontal burner bowl having a central enlargement projecting from its upper face, an oil supply duct extending downwardly through said enlargement, and a disk-like oil nozzle loosely seated on said enlargement at the 75 upper end of said duct and having holes therethrough for the passage of oil.

8. An oil burning apparatus comprising, 80 in combination, a substantially horizontal burner bowl having a central enlargement projecting from its upper face, an oil supply duct extending downwardly through said enlargement, a disk-like oil nozzle loosely seated on said enlargement at the upper end of said duct and having holes therethrough 85 for the passage of oil, an extension from said nozzle projecting into the upper end of said duct, and a rod projecting upwardly from said nozzle and forming a handle therefor.

In testimony whereof we have signed our names to this specification.

HERBERT B. NEWHALL.
